UNITED STATES PATENT OFFICE.

WILLIAM J. WOODS, OF NEW YORK, N. Y.

WHIFFLETREE-HOOK.

SPECIFICATION forming part of Letters Patent No. 367,126, dated July 26, 1887.

Application filed April 26, 1887. Serial No. 236,149. (No model.)

To all whom it may concern:

Be it known that I, WILLIAM J. Woods, of the city, county, and State of New York, have invented a certain new and useful Improvement in Devices for Attaching Traces to Whiffletrees, &c., of which I declare the following to be a full, clear, and exact description, reference being had to the accompanying drawings, forming part of this specification.

10 This invention is in the nature of an improvement in devices for attaching traces to whiffletrees and holdback-straps to thills, &c.; and the invention consists in a device for attaching traces to whiffletrees, &c., constructed 15 in the manner and for the purpose herein particularly described and claimed.

In the accompanying sheet of drawings, Figure 1 shows my device as it appears when in use on a whiffletree. Fig. 2 is a view of the 20 same partly in section. Fig. 3 is an end view of the cock. Fig. 4 is an under side view of the part with which the cock engages. Figs. 5 and 6 are side and plan views of the device when used for a holdback.

25 Similar letters of reference indicate like parts in the several views.

This invention has for its object the improvement in the fastening for whiffletrees and holdbacks heretofore patented by me on the 6th day 30 of July, 1880.

Referring to the accompanying sheet of drawings, A represents a whiffletree, which may be attached in the usual manner to the cross-bar of the thills, or to the evener when a pole is 35 used. To the ends of the whiffletrees are fixed the cocks B. The cocks B, which have the angular shape shown in Fig. 3, approximating a wedge shape, are curved, as at a, and are beveled, as at b. The base of the cocks is also beveled, as at c. This practically completes the 40 fixture on the whiffletree. A shackle, C, cast or otherwise formed, terminates in a collar, D. The upper and lower surfaces of this collar are countersunk, as at f, so that these surfaces produce a thin edge, as at g. Through the periphery of the collar D is cut a slot, E, angular in shape, to correspond to the angular shape of the cocks B, before named. The inner part of the slot is curved, as at h. A disk, F, with a 45 projecting seat, k, centrally formed therein, is next made, the disk being practically of the same diameter as is the collar D. A socket,

G, of any desired form, preferably of a form approaching the conical, as shown in Figs. 1 and 2, and with a hollow interior, is next made. 55 This socket has made in its sides two slots, l. A coiled spring, H, of suitable diameter and length to be received within the socket G, being next made, the separate parts of my device will be completed, and the separate parts are 60 united by first inserting the spring H vertically within the socket G, placing within the socket the disk F, the seat k thereof being received within the upper coil of the spring. The collar D of the shackle C is now placed 65 upon the disk, the arms m of the shackle being received within the slots l of the socket G, and the edge of that socket is turned over upon the surface of the collar D, forming thereby a retaining-flange, u, which keeps the collar of the 70 shackle fixed to the socket, and by this fixing all the several parts hereinbefore enumerated are held in place, making complete the device K.

The operation of this trace-fastening device 75 as described is as follows: The cock B being fixed to the end of the whiffletree, as stated, the device K is presented to it, with the slot E therein corresponding to the cock B; but this slot E is presented to the cock, so that the 80 thicker end of the wedge-shaped part of the cock is permitted to enter and pass under the slot E, and when this is done the cock B will be readily received within the slot E, and can be turned then at right angles to the slot E, or 85 at any angle beneath the collar D and between that collar and the disk F. The necessity for presenting the slot in the device K at an angle to the cock arises from the fact that the width of the cock at its widest part is somewhat 90 greater than the length of the slot E; hence it is apparent that the cock cannot readily pass through that slot, and so accidentally detach the device K from the cock, since when in use the strain would not be such as to present the 95 slot at such an angle and cause such accidental detachment. Now, when the cock is passed into the slot E, the curved surface a is received to some extent within the seat k of the disk F, which acts, in connection with the spring H, 100 as an elastic bearing for the end of the cock, and when the cock is so received the beveled sides b of the cock will bear against the under countersunk surface of the collar, and the bev-

bevelled base *c* of the cock will bear against the opposite countersink, *f*, of the collar, and the edge *g* of the collar, formed by these two countersinks, will be received in the neck *o* of the cock. The result of this fitting is that the cock is received within the device *K* in such a manner that it meets a smooth bearing-surface at all points, and the device *K* is enabled to turn freely and noiselessly on the cock when my device is in use.

Of course, it is apparent from an inspection of the drawings, and without special mention, that the trace *L* is passed through the shackle *C*.

To detach the traces from the whiffletree, it is simply necessary to turn the device *K* around until the slot *E* in the collar shall be coincident with the cock *B*, when by the action of the coiled spring the device *K* is tilted slightly backward and at once detached from the cock.

As is obvious, the mechanism above described is equally applicable for the attachment of a holdback, as shown in Figs. 5 and 6.

The purpose of the wedge shape of the cock and the angular shape of the slot in the collar is to prevent the accidental withdrawing of one from the other.

Having now described my invention, what I claim as new, and desire to secure by Letters Patent, is—

1. In a fastening device for traces and hold-backs, a shackle, *C*, provided with a collar, *D*, which is countersunk on both sides, and which has a tapering slot, *E*, extending from the edge of the collar part way across the same, in combination with a wedge-shaped cock, *B*, whose thickness in one direction is greater than the length of the slot *E*, and which has bevelled bearing-surfaces to receive the collar *D*, as and for the purpose described. 30

2. In a trace and holdback fastening device, 40 a shackle, *C*, terminating at one end in a slotted collar, *D*, in combination with a socket, *G*, within which said collar is secured, and in whose side are slots *l*, through which pass the arms *m* of the shackle, substantially as and 45 for the purpose described.

3. In a fastening device for traces and hold-backs, a cock of wedge-shaped form, and with a curved end, *a*, and bevelled sides *b*, and a bevelled base, *c*, combined with an elastic disk, *F*, 50 a socket, *G*, a shackle, *C*, and a slotted and countersunk collar, *D*, as and for the purpose described.

WILLIAM J. WOODS.
